UNITED STATES PATENT OFFICE.

FRED J. VIEWEG, OF JERSEY CITY, NEW JERSEY.

DESIGN FOR A BRAID ORNAMENT.

42,827.

Specification for Design.

Patented July 23, 1912.

Application filed January 29, 1912. Serial No. 674,211. Term of patent 7 years.

To all whom it may concern:

Be it known that I, FRED J. VIEWEG, a citizen of the United States, residing at Jersey City, in the county of Hudson and State of New Jersey, have invented a new, original, and ornamental Design for a Braid Ornament, of which the following is a specification, reference being had to the accompanying drawing, forming part thereof.

The figure is an elevation of a braid ornament showing my new design.

I claim:

The ornamental design for a braid ornament as shown.

FRED J. VIEWEG.

Witnesses:

AXEL V. BEEKEN,
PHILIP S. MCLEAN.
